UNITED STATES PATENT OFFICE

WILLIAM SCHNELL, OF DETROIT, MICHIGAN, ASSIGNOR TO TERNSTEDT MANUFACTURING COMPANY, OF DETROIT, MICHIGAN, A CORPORATION OF MICHIGAN

METHOD AND APPARATUS FOR MAKING A SILL PLATE

Application filed February 6, 1931. Serial No. 513,906.

This invention relates to a sill plate and method and apparatus for making the same and more particularly to the method of fabricating an ornamented sheet metal sill plate for an automotive vehicle.

In the vehicle body art it has long been a common practice to cover the portion of the body sill extending along the bottom of the door opening with a strip of sheet metal known as a sill plate. These sill plates have been ornamented for practical and esthetic reasons. Heretofore these sill plates have been rolled or formed to shape from a roll of sheet metal cut up or trimmed and then 10 ornamented by an etching process. This etching process adds considerably to the cost of manufacturing these sill plates. Hence, it is the object of this invention to produce a 15 rolled sheet metal sill plate much more cheaply than heretofore. This is achieved in a rolling mill by simultaneously rolling the sill plate to a predetermined shape and ornamenting the same. More specifically the invention comprises passing a continuous 20 strip of sheet metal between suitable rollers to simultaneously shape and ornament the same whereupon the ornamented and shaped strip is suitably cut to form sill plates having 25 rolled in ornamentations.

30 In the drawing:

Fig. 1 is a fragmentary elevation of an automotive vehicle showing a sill plate as applied to the vehicle body.

Fig. 2 illustrates an apparatus which can 35 be used to perform the method of manufacture of the sill plate.

Fig. 3 is a fragmentary detail of the shaping rollers.

Fig. 4 is a plan view of the finished sill 40 plate showing the rolled in ornamentation.

Fig. 5 is an end elevation of the sill plate shown in Fig. 4.

Referring more particularly to the drawing there is shown in Fig. 2 a form of apparatus that effectively performs the method of manufacturing a sheet metal sill plate having a rolled in ornamentation. This apparatus takes the form of a feed roll of sheet metal 1. The strip of sheet metal is passed 45 between any suitable number of pairs of

forming rollers 2. These forming rollers 2 roll a pair of longitudinal beads 3 into the sheet metal strip 4 which is passed between the rollers. The beads 3 each extend lengthwise of the sheet metal strip 4 parallel and adjacent an edge thereof. The sheet metal strip 4 is next passed through the ornamenting rolls 5. The surfaces of the ornamenting rolls 5 are suitably indented with whatever style of ornamentation it is desired to roll into the sheet metal strip 4. The ornamenting rolls 5 extend transversely of the strip 4 between the longitudinal beads 3 and grip the sheet metal strip to both pull and push the same and at the same time roll in 55 the desired ornamentation. All rolls are geared together with the correct speed relationship of the roll surfaces to form the article. These relationships vary with the shapes of the section and type of ornamentation.

In the operation of the ornamenting rolls 5 much difficulty has been encountered with the buckling and warping of the sheet metal strip 4 in front of the rolls, that is, between 60 the ornamenting rolls 5 and the forming rolls 2. This warping and buckling of the sheet metal strip 4 is produced by a number of causes. One cause is the tensioning action of the ornamenting rolls upon the surface fibers of the sheet metal strip, that is, the rollers place some of the fibers under a greater tension than others. Further, the ornamenting rolls only act upon that portion of the strip between the beads 3 and create a 65 surplusage of metal before the rolls. This surplus metal must go somewhere and the beads restrain the natural and normal flow of the metal and thus cause the strip to buckle and warp. This surplus of metal builds up in front of the ornamenting rolls until the excess folds back upon itself and thereby ruins the strip.

It has been discovered that this buckling and warping of the metal strip can be prevented by clamping the strip between a pair of wooden blocks such as those shown at 6 and 7. The upper block is provided with suitable transverse grooves and the lower block with suitable complementally trans-

verse ribs for engagement with the longitudinal ribs 3 of the strip 4. The blocks 6 and 7 are of course, fixed to the frame work of the apparatus and are bolted together by 5 the bolts 8. The pressure with which the blocks 6 and 7 clamp the strip 4 can be varied by adjusting the bolt and nut arrangement 8. Preferably the blocks 6 and 7 are clamped sufficiently close together to effect a light 10 frictional drag action upon the metal strip 4 and maintain it flat. Whether or not the clamping blocks 6 and 7 cooperate with the rolls 5 to attenuate and/or stretch the metal between the rolls 5 and the clamping blocks 15 sufficiently to accommodate the surplus metal produced by the rolling action of the ornamenting rolls, the clamping blocks do counteract the tension differential between the fibers of the metal strip 4 to prevent warping 20 of the sheet metal strip 4. The stretching of the beads to eliminate the surplusage of metal due to ornamenting, can also be accomplished with difficulty, without the use of the blocks 6 by the proper design and pressures of the 25 forming rolls, but the results are not as consistent nor as easily attained as when the blocks are used. The stretching of the fibers of the beads must be accurately controlled in the rolling mill in order to exactly equal the 30 stretch of the center portion of the strip when rolled and ornamented.

After the strip 4 passes through the ornamenting rolls 5, it is passed through straightening rolls 11 and then through suitable polishing rolls 9 which polish the same. Thereafter the rolled ornamented strip is cut into suitable lengths which are in turn cut lengthwise thereof and otherwise operated upon to form the sill plate 10 such as shown in Fig. 4. 40 The sill plate 10 is then applied to that portion of the top of the body sill which is exposed along the bottom of the door opening as shown in Fig. 1.

It is to be understood that the invention is 45 not limited to the cross-section shown but may be various types of beads and angles with appropriate ornamentation on the surfaces.

It is evident from the above description 50 that there is herein produced a sheet metal sill plate having a rolled in ornamentation, and a method and apparatus by which said sill plate is simultaneously rolled to both shape and ornament the same.

55 I claim:

1. An apparatus for operating upon a continuously moving sheet metal strip comprising in combination a pair of rollers for forming the said strip to a predetermined shape, 60 a pair of ornamenting rollers for indenting an ornamentation upon the said strip, and rigid means in front of the said ornamenting rollers for stretching the fibers of the metal strip to maintain the predetermined shape 65 and to prevent the warping of the said strip.

2. An apparatus for operating upon a continuously moving sheet metal strip comprising in combination a pair of rollers arranged to roll a longitudinal bead in the said strip, another pair of rollers for operating simultaneously with the aforesaid pair of rollers for rolling a surface ornamentation into the said strip and for pulling the strip through the forming rollers, and form maintaining means positioned in front of the said ornamenting rolls slidably engaging the said strip along a flat surface to prevent buckling of the same. 70 75

3. An apparatus for operating upon a continuous moving sheet metal strip comprising in combination a pair of rollers for rolling a pair of beads lengthwise of the strip, a pair of ornamenting rollers operating simultaneously with the aforesaid rollers for indenting an ornamentation upon the said strip between the longitudinal beads and a pair of blocks positioned in front of the said ornamenting rollers arranged to have a sliding frictional engagement with the said strip to prevent buckling of the same, the surfaces of 80 85 said blocks being adapted to maintain the form of the strip as determined by the forming rolls. 90

4. The method of fabricating a sheet metal plate comprising rolling a continuous flat strip of sheet metal to a predetermined shape, then indenting the previously rolled portion of the said strip to ornament the same, and stretching some of the fibers of the strip between the rolling and the indenting operations to overcome tensional differences in the fibers to prevent warping of the strip, the said rolling, stretching and indenting operations being carried on simultaneously upon different portions of the continuously moving strip. 95 100 105

In testimony whereof I affix my signature.

WILLIAM SCHNELL.
